UNITARY BED STRUCTURE

Albert A. Sandow, Los Angeles, Calif.

Application April 3, 1950, Serial No. 153,581

5 Claims. (Cl. 5—8)

1

This invention relates to a unitary bed structure of the type that is selectively convertible from a structure that is usable as a double bed to one that serves as twin beds.

While attempts have been made in the past to provide a convertible structure as indicated, the same invariably embodied certain major faults. When conversion was desired, such prior structures could be adjusted only from a position outside the structure and not from a position while occupying one of the beds thereof. Such conversion was accomplished by moving one bedstead relative to the other along the floor supporting the same with resulting wear on the floor surface or carpeting covering such surface. One prior attempt entailed a unitary bedstead of double width in which two sets of springs and mattresses were moved relatively and, when separated, overhung the sides of the bedstead so that pillow support of the headboard thereof was lost.

Recognizing the above faults, the present invention has for an object to provide a unitary bed structure that embodies a common support base for two single beds and is provided with means in said base operable from a position on either bed for moving both said beds together or apart as desired. By means of such a structure it will not be necessary to leave the bed to effect conversion as above.

Another object of the invention is to provide a unitary bed structure embodying novel means handy to both occupants of the beds for effecting the mentioned conversion while lying on said beds, the invention contemplating such bed-moving means that are positive and efficient and are, at all times, unobtrusive and yet easy of access.

Another object of the invention is to provide a unitary bed structure in which each bed thereof is a complete and comfortable unit in itself and includes head and foot boards that accompany the respective beds when moved to adjusted position, and, when moved together, constitute a wide and comfortable double bed.

Other objects of the invention are to provide novel combinations and arrangements of elements, simple and inexpensive details of construction, and a structure that has general superiority and serviceability.

The accompanying drawings show a preferred embodiment of the present invention. In said drawings,

Fig. 1 is a cross-sectional view of a unitary bed structure according to the present invention, the same being shown arranged as a double bed.

Fig. 2 is an end elevational view as seen from

5

the footboard end of said structure and arranged as a twin bed unit.

Fig. 3 is an enlarged cross-sectional view as taken on line 3—3 of Fig. 2.

Fig. 4 is a similarly enlarged fragmentary sectional view as taken on line 4—4 of Fig. 2.

Fig. 5 is a side elevational view of the bed structure drawn to the scale of Figs. 1 and 2.

Fig. 6 is a plan view of one-half of a novel base employed in the bed structure, said view being taken substantially on line 6—6 of Fig. 5.

Fig. 7 is an enlarged plan sectional view of operating means embodied in the base for simultaneously and relatively moving two beds mounted on said base.

Fig. 8 is a side elevational view thereof.

Figs. 9 and 10 are cross-sectional views of two selective positions of the operating means, said views being taken on line 9—9 of Fig. 8.

Fig. 11 is a plan sectional view of the base of the bed structure, the view also being taken on line 6—6 of Fig. 5.

Fig. 12 is an enlarged fragmentary detail view, partly in section, of a coupling connecting the sections of a feed screw used in the structure.

The unitary bed structure that is illustrated comprises, generally, a base 15, two substantially similar beds 16 and 17 mounted on said base, roller means 18 affording frictionless movement of the beds laterally relative to each other and to the base, means 19 extending transversely of the base and embodied therein for effecting the mentioned movement of the beds, and operating means 20, one at each side of the base, for operating the bed-moving means 19.

The base 15 comprises two frames 21 arranged side by side, and a connecting portion 22 for said frames. The base, therefore, is generally H-shaped, as shown best in Fig. 11.

The frames 21 are similar but oppositely formed and may be constructed of wood or metal, as desired, to have a flat rectangular shape generally proportioned in size and shape to be substantially as long as a conventional single bed but narrower than such a bed. Assuming that eighteen inches is the desired spacing between beds 16 and 17 when separated, frames 21 are each made to be some nine inches narrower than said beds. Regardless of what material the frames are made, they will be suitably internally braced to obviate distortion and, if desired, may be covered with metal or plywood panels.

The connecting portion 22 is somewhat flatter than the frames 21 and is made to be as low as possible so that the same may be stepped over

2

and on and offers minimum impedance to the feet. Said portion 22 is covered with a flatly curved floor member 23 that rises gradually from the floor supporting the structure. It will be seen that there is ample room between the separated beds 16 and 17 for free movement of a person.

Each bed 16 and 17 comprises a generally conventional single bed comprising a headboard 24, a baseboard 25, and side rails 26 connecting said boards. The usual spring 27 and mattress 28 are provided for each bed. It will be noted that the headboard and baseboard of both beds are spaced so as to be beyond the ends of frames 21 and extend toward, but clear of the support floor, thereby concealing the frames when viewed from either end of the structure.

The means 18 is shown as comprising three channels 29 mounted transversely on each frame 21. The base of each channel is slotted and, from beneath, a plurality of transversely spaced rollers 30 extend through the slots in the channels. The inner sides of the headboard and baseboard and an intermediate transverse support member 31 extending downward from each pair of rails 26, mount transverse cleats 32 that rest upon rollers 30. It is, therefore, clear that beds 16 and 17 can roll sidewise relative to frames 21 by the frictionless support afforded by rollers 30.

Each bed, in alignment with connecting portion 22, is provided with a downwardly extending board 33 at the lower end of which is secured a nut 34. The means 19 is engaged with said nuts and comprises a feed screw 35 extending through the nuts and from side to side of base 15. The nut 34 and the screw on one side have right-hand threads and those on the other side, left-hand threads, so that rotation of said screw will effect simultaneous movement of the beds toward or from each other according to the direction said screw is rotated. The inner frame sides 36 limit movement of the beds toward each other, and parallel abutment members 37 limit outward movement of said beds. For convenience of assembly, the feed screw 35 is made in two sections that join as by a coupling 38. Also, the base 15 can be knocked down for easy transportation by detaching portion 22 from the frames 21 and separating the screw ends at coupling 38.

It will be noted that screw 35 is nearer the head end of the structure so that a person lying on either bed 16 or 17, can easily reach down over the outer side of the bed to manipulate the means 20 for effecting rotation of screw 35 and resulting movement of the beds on their support roller means 18. In order that said means 20 may not extend beyond the outer sides of frames 21, when not in use, the outer ends of screw 35 terminate short of the outer side members 39 of said frames. As shown, an inwardly formed portion 40, on each side of the base 15, defines a recess 41 in which the means 20 is accommodated, one on each side of the structure.

The operating means 20, on each side, comprises a bevel gear 42 on the end of feed screw 35, a second bevel gear 43 in mesh therewith and carried by a vertical stud 44 mounted on a bracket 45a that is fixed to frame portion 40. A ratchet wheel 45 is keyed to stud 44. A handle 47 is provided with a pair of ears 48 which are mounted for free rotation on said stud on either side of ratchet wheel 45. The handle, which is horizontally movable, carries a pair of pivoted pawls 49 the tail portions of which are urged

apart by a spring 50 so that the dog ends 51 of said pawls are urged inward toward each other. A rotational sleeve 52 is mounted on the handle and held in place by a collar 53 at one end and by the mentioned ears 48 at the opposite end. Recesses 54 are provided in the handle to accommodate the tails of pawls 49 and are of sufficient depth to permit movement of the same toward each other. The sleeve 52 is provided with an internal eccentric cam face 55 that extends through an arc of some 135° leaving the remainder 56 of the sleeve bore concentric with the outer surface of the sleeve.

As seen in Figs. 7 and 9, when the sleeve 52 is rotationally adjusted to align concentric portion of the bore with one pawl 49, the spring 50 will press the dog end 51 of said pawl into engagement with the teeth of ratchet wheel 45. At the same time, the middle part of cam face 55 will inwardly press the tail of the other pawl to retract its dog end away from said ratchet wheel. Consequently, as the handle 47 is reciprocated, the first-mentioned pawl will alternately drive and ratchet over the teeth of the ratchet wheel 25 to rotate gears 42 and 43 and rotate feed screw 35 in one direction. By turning sleeve 52 through an arc of 180°, the retracted pawl is brought into operative engagement with the ratchet wheel and the previously operative pawl is retracted. Now, 30 when the handle 47 is reciprocated, the feed screw is rotated in the opposite direction.

By the above simple means, beds 16 and 17 can, with little effort and from a position on one of them, be moved apart or brought together, as desired. Since the above operation is desired to be effected from either side of the structure, it is necessary to uncouple the operating means at both ends so that, at any time, one or the other can be manipulated. In the present device, by 40 rotating sleeve 52 through 90°, from either operating position, as in Fig. 10, the cam face 55 will retract the dog ends of both pawls, simultaneously, thus uncoupling handle 47 from the feed screw 35.

While such uncoupling rotation of sleeve 52 may be accomplished manually, the same is preferably automatically effected when the handle is swung to a non-protruding position in recess 41. For this purpose, the sleeve 52 is provided with a suitable number of suitably arranged radial projections 57 which are positioned so that one of them encounters a forwardly projecting bracket 58 fixed on frame portion 40 when the handle is swung to an out-of-the-way position. The sleeve will be rotated some 90° from either operating position to achieve the position of Fig. 10 in which the handle 47 is uncoupled from the feed screw 35.

Since nuts 34 and feed screw 35 are self-locking on their threads, the beds will retain their adjusted position. Also, the engagement of said nuts and screw counteracts any tendency for the beds to tilt by excess of weight on one side or the other. In any case, a rail 59 may, if desired, be provided beneath each set of rollers 30 and carried by the headboard and footboard of each bed to aid in counteracting any tendency of the beds to tilt.

While manually operable means for adjusting the beds 16 and 17 has been disclosed, it will be evident that the same can be accomplished by motor-operated means and controlled by push-button switches carried by the headboard within reach of either occupant of the beds.

The foregoing disclosure should be considered

as exemplary since the means thereof can be modified and yet achieve the functions hereinabove described. Accordingly, I desire to reserve to myself such modifications of the invention that may fall within the scope of the appended claims.

Having thus described my invention, what I desire to obtain by Letters Patent, is:

1. A unitary bed structure comprising a base, two beds mounted side by side on said base, means extending across the base and connected to the two beds to move the same relative to the base and to each other, and means to operate the bed-moving means from a position on either bed, said latter means comprising selective ratchet devices on each outer side of the frame and including a pivoted horizontally movable operating handle.

2. A unitary bed structure comprising a base formed to have two spaced parallel frames and a portion connecting said frames, a bed mounted upon each frame, elongated bed-moving means extending across the base and through the mentioned connecting portion, a member extending downwardly from each bed and adjustably connected to intermediate portions of said bed-moving means, and a device on each end of the bed-moving means to operatively move the latter adjustably to move the two beds simultaneously relative to each other.

3. A unitary bed structure comprising a base formed to have two spaced parallel frames and a portion connecting said frames, the same constituting a flat H-shaped supporting structure, a bed mounted on each frame to overstand the same, the beds being wider than the frames and 35

movable relative to the frames to overhang the inner or outer sides of the frames, selectively, means connected to the beds and extending transversely of the frame and through the connecting portion thereof to move the beds simultaneously to overhang the inner or outer sides of the base frames, as desired, and operating means for the bed-moving means accessible to an occupant of either bed.

10 4. A bed structure according to claim 3: the operating means comprising an occupant-controlled device on each end of the bed-moving means, and a separable coupling connecting each said end and the operating device connected thereto.

15 5. A bed structure according to claim 3: the bed-moving means comprising a feed screw, the operating means comprising an occupant-controlled device on each end of the feed screw, and 20 a separable coupling connecting each said screw end and the operating device connected thereto.

ALBERT A. SANDOW.
